UNITED STATES PATENT OFFICE

118,590

DESIGN FOR A TEXTILE FABRIC

Louis Bondy, Baltimore, Md.

Application August 30, 1939, Serial No. 86,939

Term of patent 3½ years

To all whom it may concern:

Be it known that I, Louis Bondy, a citizen of the United States and resident of Baltimore, in the county of Baltimore and State of Maryland, have invented a new, original, and ornamental Design for Textile Fabric, of which the following is a specification, reference being had to the accompanying drawings, forming a part thereof, showing my new design,

Fig. 1 is a plan view of a textile fabric showing my design;

Fig. 2 is a detailed view of the fabric shown in Fig. 1; and

Fig. 3 is an enlarged view of a section of the fabric shown in Fig. 1.

The design consists of an allover loosely woven yarn interspersed with nubs as shown.

I claim:

The ornamental design for a textile fabric, as shown and described.

LOUIS BONDY.
